UNITED STATES PATENT OFFICE.

GEORGE B. WEBB, OF WESTFIELD, NEW JERSEY, ASSIGNOR TO WYCKOFF, SEAMANS & BENEDICT, OF ILION, NEW YORK, A CORPORATION OF NEW YORK.

TYPE-WRITING MACHINE.

SPECIFICATION forming part of Letters Patent No. 720,302, dated February 10, 1903.

Application filed January 9, 1900. Serial No. 883. (No model.)

To all whom it may concern:

Be it known that I, GEORGE B. WEBB, a citizen of the United States, and a resident of Westfield, in the county of Union and State of New Jersey, have invented certain new and useful Improvements in Type-Writing Machines, of which the following is a specification.

The present invention relates to tabulating devices for type-writing machines wherein the carriage is released at any point in its forward traverse from the control of its escapement mechanism, is quickly advanced, and is automatically arrested at a given point or points or at variable distances therefrom, the primary object of the invention being to provide for writing from time to time a variety of tabular work with a minimum of adjustments in the machine.

Heretofore machines of the class referred to have been provided with a row or series of independently-adjustable column-stops on the carriage and with a series of denomination-stops on the framework independently movable into and out of position for coaction with the said column-stops. In this prior construction it is necessary after the column-stops have been set and used for one tabular form to reset many or all of them whenever it is desired to write upon a tabular form differing from the first, and of course when it is again desired to write upon tabular forms of the first-named kind the column-stops have to be set again.

According to the present invention a number of rows or sets of column-stops is employed, and means are provided for bringing one or another of these sets into position for coaction with the said denomination-stops. Various methods of mounting and moving said sets of stops may be employed without departing from the scope of my invention; but I prefer to arrange them upon a rotatable rod or bar, the stops for each tabular form projecting therefrom in a different direction from the stops for the other form or forms. By rotating the bar the stop or row of stops for any desired form may be moved to position for coaction with said denomination-stops and the previously-used row of stops simultaneously moved out of working position.

Preferably said column-stops are adjustable along said bar or rod rather than being made integral therewith or immovably attached thereto, as this adjustability provides for the writing of an indefinite number of different tabular forms. By preference the rod or bar is polygonal and is provided with notches or teeth on two or more sides thereof, and the column-stops may be provided with springy forks to engage with teeth on two opposite sides of the bar.

To these ends the invention consists of certain features of construction and combinations of devices hereinafter described, and more particularly pointed out in the appended claims.

The preferred form of the invention is illustrated in the accompanying drawings, forming part of this specification, in which—

Figure 1 is a plan view, partly broken away and with certain parts omitted, of a type-writing machine in which the invention is embodied. Fig. 2 is a central vertical transverse section with parts omitted of the machine shown in Fig. 1. Fig. 3 is a perspective view of a revoluble rod or bar shown in Figs. 1 and 2 and having rows of column-stops or tappets projecting therefrom in different directions. Fig. 4 is a longitudinal sectional view of the rod shown in Fig. 3, the central part of the rod being omitted, showing the method of mounting said rod for rotation. Fig. 5 is a perspective view of a journal for the rod shown in Fig. 3, said journal being partly cut away or slabbed off, so as to form two opposite parallel flat sides thereon. Fig. 6 is a transverse section of the rod shown in Figs. 3 and 4, the section being taken through a journal at its flattened sides. Fig. 7 is a view showing a column-stop in side elevation and its carrier in cross-section. Fig. 8 is a view showing two column-stops integral with each other and projecting in different directions from a common carrier or support. Fig. 9 is a view showing three integral column-stops projecting in different directions from a common carrier. Fig. 10 is an edge view of the stop shown in Fig. 9. Fig. 11 is a perspective view of another construction of the column-stop carrier having teeth on four sides thereof. Fig. 12 is a view showing a plain

column-stop and a multiple column-stop in side elevation and also a cross-section of the carrier shown in Fig. 11. Fig. 13 is a perspective view of a journal for the revoluble 5 stop-carrier when said carrier is provided with more than two longitudinal rows of column-stops or when the stops thereon project therefrom at right angles to each other.

The same numeral of reference will be used 10 to designate the same part throughout the drawings.

1 is the base-frame of the Remington No. 6 type-writing machine.

2 represents standards rising from the base 15 1; 3, a top plate or type-ring attached to the standards 2; 4, type-bars connected with the type-ring 3, as usual; 5, key-levers with which the type-bars 4 are connected by rods or connections 6; 7, a carriage to which a letter-spacing rack 8 is connected by pivoted arms; 9, a pinion meshing with the rack 8; 10, an escapement-wheel suitably connected to the pinion 9; 11, escapement-dogs coacting with the wheel 10 to control the letter-space movement of the carriage 7; 12, a platen connected to the carriage 7, so as to move therewith.

13 represents arms secured to the frame of the carriage 7 by hooks 14 and screws 15 16. The screws 15 pass above the transverse bar 30 of the carriage 7 and engage or bear against the sockets 17 of the usual removable paper-shelf, (not shown,) and the screws 16 engage beneath the said transverse bar of the carriage 7 and abut against a vertical part thereof. The arms 13 extend rearwardly and are curved downwardly from the carriage 7 to about a horizontal plane through the shaft of the pinion 9. At their rear ends the arms 13 are provided with transverse slots 18. To 40 each arm 13 an elongated journal-block 19 is attached by means of a screw 20, which passes through and is adjustable along the said slot 18 and engages with a threaded hole 21 in the said block. The blocks 19 extend horizontally toward each other, or in the direction of motion of the carriage, and each is fitted or provided with a cylindrical journal piece or stud 22, which is preferably made separately and forced into a bore in the said block, although 50 obviously the block and journal may be made in one piece, if desired.

Extending between the inner ends of the blocks 19 and abutting against cylindrical shoulders or bosses formed thereon is a bar 55 or rod 23, preferably polygonal in cross-section (shown as square in the drawings) and journaled on the said studs 22. Each stud or journal 22 is slabbed off at 24 upon opposite sides thereof. Holding-pins 25, secured 65 to springs 25^a, the latter being fastened by screws 26 to the bar, are secured to each end portion of the rod 23 and pass through radial perforations 25^b in the rod 23 and bear against the flattened parts 24 of the studs 22. By the 75 application of force to the rod 23 the same may be turned, the spring-pins 25 yielding, as indicated in Fig. 6, to permit the rod to

turn and then engaging the opposite flat surface 24 to hold the rod. The rod shown at Fig. 3 is provided with transverse notches, 70 recesses, or kerfs 27^a upon two sides thereof, forming rectangular teeth 27 at letter-space intervals. The rod may be provided upon one or both plain sides with a scale or scales 28, corresponding in its markings to the usual 75 carriage and platen scales and also to the teeth 27 or notches 27^a.

The column stops or tappets comprise metal plates of a thickness to fit closely in the kerfs 27^a, being forked for the purpose of engaging 80 with the said rod or tappet-carrier 23 at opposite sides thereof. The form of column-stop shown in Fig. 7 comprises a carriage-arresting portion 29 and two parallel arms 30, separated by a distance equal to or slightly 85 greater than the distance separating the bottoms of opposite kerfs in the rod 23, it being understood that the teeth 27 at opposite sides of the rod 23 are in line or squarely opposite each other. In order to prevent accidental 90 displacement of the column-stop from the rod 23, one of the arms 30 is formed or provided with a beveled projection or hooked portion 31, which extends inwardly and engages with an edge at the bottom of a kerf, as indicated in 95 Fig. 7, the inherent springiness of the metal of the column-stop sufficing to permit of the placing of the column-stop in position on the rod 23 and then to cause the tooth 31 to hold it in place with sufficient force to prevent accidental movement thereof. The forked column-stops are, however, readily removable from the rod 23 and may be inserted between pairs of opposite teeth at any point on the rod, thus providing for their adjustment to 100 form stops for different kinds of tabular work. The column-stops shown in Fig. 7 may be placed upon the rod 23 from either side thereof, as indicated in Fig. 3, the latter figure showing two longitudinal rows or series of 105 stops upon the rod. All of the stops move simultaneously with the rod when it is rotated or revolved for the purpose of moving either row into or out of working position. In order to provide for the contingency in which different tabular forms may have one or more columns or ruled lines falling upon or beginning at the same division of the type-writer scale, some of the adjustable column-stops may have 110 their working arms or teeth offset by a letter-space distance, so that when one of these offset stops and one not offset are placed in adjacent kerfs upon the rod 23 their working faces will lie in the same vertical plane and will arrest the carriage in the same position, 115 whichever stop may have been turned to working position. Such offsets are indicated at 32 in Fig. 3.

The devices shown in the drawings for co-action with the column stops or tappets 29 in 120 arresting the carriage at variable distances from points predetermined by adjustment of the tappet along or upon the rod comprise a series of denomination-stops, preferably in

the form of independently-movable blades 33, operating-levers 34 therefor, key-actuated horizontal push-rods 35, and certain accessories. The denomination-stops 33 are preferably in the form of metal plates arranged on edge and side by side in rear of the rod 23. They have independent sliding or plunging motion forward and back between parallel vertical jaws or guides 36, which are united by a horizontal cross-head 37 of a frame 38. The latter is secured at its lower end to the base-frame 1 by lugs 39, which catch over the top edge of the base, and lugs 40, which extend forwardly under the lower edge of the rear plate of the base-frame and are also provided with screws 41, having coned points which engage with the front edge or side of the said rear plate, as indicated in Fig. 2, to securely hold the frame 38. In addition the latter is rigidly connected with the type-ring or top plate 3 by means of horizontal stay-rods 42, which pass through ears 43 on the frame 38 and are firmly and adjustably attached thereto by means of nuts 44, working on the threaded ends of the stay-rods 42. At their front ends the stay-rods 42 are provided with jaws 45, which hook under the rear flange of the top plate 3, said flange being clamped between the said jaws 45 and screws 46. Each denomination-stop 33 is formed with a lug 47 upon the upper edge thereof and also with a longitudinal slot 48. A lateral pin 49 is formed or provided in a recess 49^a, formed upon one side of each stop 33, the end of the pin being flushed with the side of the stop. Transverse guide and supporting rods 50 extend through the slots 48 and are supported at their ends in the jaws 36. Any desired number of loose rings or rolls 50^a may be placed along said rods 50. Each lever 34 is formed with an open slot 34^a at its upper end for engagement with the pin 49 of the corresponding stop 33, the end of the lever 34 being of such a thickness as will enable it to lie in the recess 49^a. The levers 34 are pivoted intermediate their ends upon a transverse rod 51, which is secured in the frame 38. At their lower ends the levers 34 are reduced in width and pass through eyes formed in the ends of horizontal slide-rods 35. The slide-rods 35, which underlie the stop-operating levers 34, are guided at their rear ends in holes formed in a cross-bar 52 of the frame 38 and at their front ends in holes formed in a cross-bar 53, which is clamped to the front flange of the base-frame 1 by jaws and screws 54. At their front ends the push-rods 35 are provided with finger keys or buttons 55, which may be suitably marked to represent various denominations or orders. Each rod 35 has a collar 56 adjustably secured thereto by a setscrew 57. A coiled draw-spring 58 is attached at one end to each collar 56, as by the screw 57. The other end of each spring is attached to the front bar 53, as by screws 59, the said springs being tensioned to draw the push-rods 35 forwardly of the machine, so as to

cause the levers 34 to hold the denomination-stops 33 rearwardly and out of the path of the tappets 29.

The carriage may be released in any suitable manner from the control of the escape-movement-dogs 11 to permit it to run forward freely under the influence of its spring-drum 60, which is, as usual, connected to the carriage by a strap 61. The device shown for this purpose comprises a horizontal transverse universal bar 62, arranged in front of the lugs 47 of the denomination-stops 33 and provided with vertical arms 63, which fork the jaws 36 and are pivoted at 64 to the frame 38. One of the arms 63 is in the form of a bell-lever and extends forwardly, as indicated in Fig. 2. Said forward arm of the bell-lever is connected by a vertical link 65 with a crank-arm 66 on a forwardly-extending horizontal shaft 67, which is provided with a returning-spring 67^a and is journaled in lugs 68 of a frame 69, the latter being attached to the top plate 3 by a screw 70. At its front end the shaft 67 is provided with a bent horizontal crank-arm 71, upon the free end of which is mounted a roller 72, arranged under and normally just out of contact with the teeth of the rack-bar 8. The crank-arms 66 and 71 extend in opposite directions from the shaft 67, as indicated in Fig. 1.

The operation of the above-described devices is as follows: Whenever it is desired to run the carriage forward a number of letter-space distances in order to begin the writing at any desired point, a row of column-stops 29 is first arranged upon one side of the rod 23 so that each stop will be opposite that graduation or scale-mark upon said rod which corresponds with the scale-mark upon the platen-scale opposite which it is desired to print the decimal-point in or where it is desired to begin writing words. Then by operating that one of the denomination-keys 55 which corresponds to the highest order in the number to be written the corresponding rod 35 is pushed rearwardly and the corresponding lever 34 is rocked to move the corresponding denomination-stop 33 forwardly into the path of the tappets 29 at the rear of the rod 23. In its forward motion the stop 33 causes the universal bar 62 to move forwardly, thus vibrating downwardly the horizontally-extending arm 63 and pulling down the connecting-rod 65 and the crank-arm 66, thereby causing the shaft 67 to rock and raise the crank-arm 71 and roller 72, which last contacts with the rack 8 and lifts it out of mesh with the pinion 9, thus freeing the carriage and permitting it to run forward under the influence of its spring-drum until the first rear tappet 29 at the right of the forwardly-projected stop 33 is brought against the said projected stop, thus arresting the carriage. Upon release of the key 55 the connected spring 58 draws the rod 35 forwardly, thus vibrating the lever 34 and moving the projected denomination-stop rearwardly to normal

position and out of the path of the working tappets. Simultaneously the weight of the rack 8 or the usual spring bearing thereon (not shown) carries the rack downwardly and 5 into mesh with the pinion 9, the universal bar 62 and parts operated thereby being caused to return to normal position by the tension of the spring 67^a on said shaft 67, the latter moving as fast as the connections between it and the lug 47 of the projected stop will permit. The platen 12 is now in position such that the number may be written thereon in proper relation to the decimal-point, it being understood, of course, that 10 the left-hand slide or stop 33 in Fig. 1 corresponds to the decimal-point and that the stops at the right thereof correspond, respectively, to units, tens, hundreds, &c., in the order named. The front ends of these 15 stops are beveled at the left-hand sides, and the tappets 29 are tapered rearwardly, so as to prevent the latter from blocking the former in their forward movements. After writing the desired number the denomination-key 55 corresponding to the highest order in the next number to be written is operated and the carriage again positioned. After writing the second number a key 55 is operated for positioning the carriage so that 20 the third number can be written, and so on to the end of the line of writing. The carriage is then returned to begin a new line and the successive operations repeated. When it is desired to do a different class of tabular work upon the machine, it is unnecessary to disturb in any way the relative individual arrangement of the column-stops that are already set. Instead of doing so the rod 23 is turned in its bearings, so as to bodily 25 remove the previously-used set of tappets from working position and simultaneously bring another face of the bar 23 opposite the denomination-blades 33. A fresh set of tappets may be then adjusted along said face of 30 the bar, using either plain or offset tappets, or both, as may be found necessary or desirable. The writing of the tabular form may then proceed as usual. The machine being now provided with two sets of differently-arranged tappets, either of which sets may be 35 brought independently to working position when required, it follows that either class of tabular forms may be written at any time and from time to time without the necessity of disturbing the tappets in either set—that is, without the necessity of disturbing the arrangement of tappets one to another used in one kind of tabular work in order to do some other kind of tabular work. It will further 40 be observed that a third and a fourth set of tappets may likewise be arranged upon a single bar, so that the machine may be provided at one time with means for writing four different kinds of tabular forms, which it is believed will suffice for ordinary purposes.

Of course instead of arranging the tappets or column-stops in sets in the manner above

described the several sets may be arranged in proper order on the several sides of the bar before the commencement of any writing 70 at all.

In the construction illustrated at Fig. 8 two column-stops 29 and 29^a are formed integrally with each other and come opposite adjoining faces of the rod 23. This construction may be termed a "multiple tappet" or "multiple column-stop" and may be employed in connection with single or other differently-formed stops, so that the rows of stops at the different sides of the bar or carrier may be differently disposed for different pieces of work.

In the construction illustrated at Figs. 9 and 10 the three teeth 29, 29^a, and 29^b of the multiple tappet are formed integrally and 85 project from three faces of the rod 23. The teeth 29^a and 29^b are offset at 32, one to the right and the other to the left, for purposes hereinbefore set forth.

In the constructions illustrated in Figs. 11, 90 12, and 13 teeth 27 are cut upon all four sides of rod 23, so that tappets may be placed thereon in a great variety of ways. The journals 22 are slabbed off on four sides at 24 to provide four bearings for the pins 25. (See Fig. 95 13.)

From the foregoing description it will be seen that a plurality of sets of column-stops is combined with a set of denomination-stops, the latter being adapted to coöperate at will 100 with any of the column-stops, and that in carrying out the invention provision is made for moving any set of column-stops into co-operative relation with the denomination-stops and for withdrawing them at will. 105

By means of the slot 18 and the screw 20 the stop-carrying rod 23 may be adjusted in the direction of the escapement movements of the carriage, so that any tappet arranged upon said rod may have the desired relation 110 to the blades 33, it being customary in tabulating mechanisms to arrest the carriage about midway between two consecutive letter-space positions thereof, so that upon releasing the carriage from the control of the 115 tabulating devices it may have a slight advance movement or "drop" before being arrested by its escapement devices, whereby a correct positioning of the carriage by the tabulating mechanism is insured. The column-stops may be withdrawn simultaneously 120 from coöperation with the denomination-stops without disturbing said adjustment at 18.

While I have illustrated and described the 125 preferred form of the invention, I do not limit myself to the specific forms of column-stops or column-stop carrier shown nor to the specific method set forth of moving the carrier to bring the different sets of column-stops into 130 working position, since in so far as the broad invention is concerned other means or methods of mounting the column-stops may be adopted without departing from the scope of

my invention. The carrier for the column-stops may be otherwise moved for securing coaction between the desired row of column-stops and the denomination-stops 33; nor is it essential to my invention that the carrier 23 should be so located as that the tappets should project horizontally when in working position.

While I have shown and described a plurality of sets of column-stops as arranged at one time in the machine and as having a common support, yet the invention is not limited to this arrangement, inasmuch as it is broadly new to adapt a plurality of sets of column-stops to be used at different times as occasion may arise in the tabulating mechanism of a type-writing machine without the necessity of disturbing the relative arrangement of the stops in any set at any time, and so long as suitable provision is made for enabling this to be done by mere manipulation of the parts and without the employment of mechanical skill it is not essential that all the column-stops in all of the sets be carried upon the machine at one time.

What I claim as new, and desire to secure by Letters Patent, is—

1. In a type-writing and tabulating mechanism, the combination of a plurality of independently-usable rows of column-stops and a set of denomination-stops adapted to coöperate with each row of column-stops.

2. In a type-writing machine, the combination with a carriage, of a tabulating mechanism therefor, including a plurality of rows of column-stops, a denomination-stop mechanism, and a single set of denomination-keys adapted to actuate all of the stops in said denomination-stop mechanism.

3. In a type-writing and tabulating mechanism, the combination with a set of denomination-stops, of a plurality of rows of prearranged column-stops, any of which rows may be moved into coöperative relation with the denomination-stops.

4. In a type-writing and tabulating mechanism, the combination of a set of denomination-stops, a plurality of rows of column-stops, and a means whereby one row of column-stops may be moved out of operative relation to the denomination-stops, and the other row simultaneously moved into operative relation to said denomination-stops.

5. In a type-writing and tabulating machine, the combination with a denomination-determining mechanism, of a series of independent adjustable column-tappets arranged in a row upon a common support and adapted to coöperate with said denomination-determining mechanism, said column-tappets being so constructed and supported that they may be withdrawn bodily at will from coöperation with said denomination mechanism without the necessity of disturbing the arrangement of said tappets relatively to one another in said row, whereby said set of tappets may be

temporarily withdrawn or replaced by another set and afterward returned bodily and in their original arrangement to coöperative relation with said denomination mechanism.

6. In a type-writing and tabulating machine, the combination of a carriage, a stop upon the framework of the machine, a row of independently-adjustable column-stops arranged upon the carriage and simultaneously adjustable thereon into and out of position for coöperation with the first-mentioned stop at the tabulating operation, and means for causing a relative transverse movement between said stop and said row of stops.

7. In a type-writing and tabulating mechanism, the combination of a carriage, carriage-feeding mechanism, including a rack, and a plurality of independently-usable rows of column-stops mounted upon a single carrier and movable as a whole when any row is moved out of or into working position.

8. In a type-writing and tabulating mechanism, the combination with a carriage, of a rod mounted for rotative adjustment and a plurality of longitudinal rows of column-stops arranged on said rod and moved simultaneously thereby so as to move one row out of operative position and another row into operative position.

9. In a type-writing and tabulating mechanism, the combination with a carriage, of a bar, column-stops on and arranged in different radial positions relatively to said bar, a stop movable into and out of position for coaction with stops at one side of said bar, and means for varying the position of the bar and its column-stops relatively to said stop to bring different radial column-stops into position for coaction with said stop.

10. In a type-writing and tabulating mechanism, the combination of a carriage, a bar or rod carried thereby, column-stops adjustable along and arranged in different radial positions relatively to said bar, a stop movable into and out of position for coaction with column-stops at one side of said bar, and means for varying the position of the bar and its column-stops relatively to said stop to bring different radial column-stops into position for coaction with said stop.

11. In a type-writing and tabulating mechanism, the combination with a carriage, of a bar or rod mounted for rotative adjustment to present different longitudinal lines or faces in a given direction, column-stops on and arranged in different radial positions relatively to said bar, and a stop movable into and out of position for coaction with stops projecting from said bar in said given direction.

12. In a type-writing and tabulating mechanism, the combination of a carriage, a bar carried thereby and mounted for rotative adjustment thereon to present different longitudinal lines or faces in a given direction, column-stops adjustable along and arranged in different radial positions relatively to said

- bar, and a stop movable into and out of position for coaction with column-stops projecting in said given direction from said bar.
13. In a type-writing and tabulating mechanism, the combination of a carriage, a bar, sets of column-stops on and arranged in different radial positions relatively to the said bar, a series of blades or stops severally movable into and out of position for coaction with the set of column-stops at one side of said bar, whereby the said carriage may be arrested at different distances from points determined by said column-stops, and means for varying the position of the bar and its radial stops relatively to the said blades or stops, so as to bring a different set of radial stops into position for coaction with the said blades or stops. 70
14. In a type-writing and tabulating mechanism, the combination of a carriage, a bar carried thereby, a plurality of longitudinal rows of column-stops adjustable along said bar, a series of denomination-stops movable into and out of position for coaction with a row of said column-stops, and means for varying the position of the bar and its rows of column-stops relatively to said denomination-stops so as to bring different rows of denomination-stops into working position. 80
15. In a type-writing and tabulating mechanism, the combination of a rod mounted for rotative adjustment and having column-stops projecting therefrom in a number of directions, a series of denomination-stops arranged to coact with stops at one side of said rod, and a carriage arranged to be arrested by said stops. 85
16. In a type-writing and tabulating mechanism, the combination with a set of denomination-stops, of a plurality of sets of independently-usable column-stops arranged upon a bar, supports for the bar, and spring mechanism for temporarily holding the bar in either of a plurality of positions to enable the coöperation of all of said sets of column-stops with said denomination-stops. 90
17. In a type-writing and tabulating mechanism, the combination of a denomination-determining mechanism, a rod, a column-stop thereon, and a spring device for holding said rod in either of two positions, in one of which said stop is in working position and in the other of which it is out of working position. 95
18. In a type-writing and tabulating mechanism, the combination of a revoluble rod, column-stops projecting in different directions from said rod, and a spring device for holding said rod in position when any of said stops is in its working position. 100
19. In a type-writing and tabulating mechanism, the combination of a rod, a fixed block at and opposite each end of said rod, journals projecting from said blocks into bores in the ends of said rod, flat faces on said journals, 105 spring-pins adapted to bear on said faces to retain said rod yieldingly against rotation, and a column-stop on said rod and adapted to be rotated thereby into and out of working position. 110
20. In a type-writing and tabulating mechanism, the combination of a pair of endwise-adjustable journal-blocks, a rod journaled at its ends upon said blocks, and a plurality of sets of column-stops adjustable along said rod. 115
21. In a type-writing and tabulating mechanism, a bar provided with means for carrying a plurality of rows of independently-adjustable tappets, said bar being so mounted that it may be moved crosswise of its length so as to simultaneously move all of the tappets thereon to a different position. 120
22. In a type-writing and tabulating mechanism, the combination of a revoluble rod having recesses, and a forked plate having carriage-arresting teeth projecting in different directions, the forked portion of said plate being adapted to engage detachably with two recesses in said rod. 125
23. In a type-writing and tabulating mechanism, the combination of a revoluble rod having recesses, and a forked plate having carriage-arresting teeth projecting in different directions, and at least one tooth being offset a letter-space distance, the forked portion of said plate being adapted to engage detachably with two recesses in said rod. 130
24. In a type-writing and tabulating mechanism, the combination of an independently-movable polygonal rod provided with teeth on a number of sides thereof, and forked carriage-arresting tappets straddling said rod and engaging with teeth on two sides thereof, said tappets projecting in diverging directions from said rod. 135
25. In a type-writing and tabulating mechanism, the combination of a polygonal rod provided with teeth on at least two sides thereof, and a forked column-stop straddling said rod and engaging with teeth on two sides thereof and provided at the free end of one arm of the fork with an inwardly-projecting tooth or lug arranged to overlap an edge of said bar when in place thereon, to hold the stops against accidental displacement. 140
26. In a type-writing and tabulating mechanism, the combination of a polygonal rod provided with teeth on a number of sides thereof, and a forked column-stop straddling said rod and engaging with teeth on two sides of said rod, and the working face or portion of said stop being offset to bring it into a plane a letter-space distance away from the forked portion. 145
27. A thin or plate-like offset tappet adapted for coöperation with the denomination-stops of a type-writing and tabulating machine, the toothed portion of the tappet being out of line with the supporting portion thereof but substantially parallel therewith. 150
28. A thin or plate-like multiple-toothed column-locating tappet for coöperation with the

denomination-stops of a type-writing and tabulating mechanism, and having the teeth thereof arranged at angles to each other.

29. A tappet for coöperation with the denomination-stops of the tabulating mechanism of a type-writing machine comprising a plurality of integral carriage-arresting teeth arranged at angles to each other and so that when one of said teeth is in working position the other teeth are in inoperative position.

30. A tappet for coöperation with the denomination-stops of the tabulating mechanism of a type-writing machine comprising a plurality of carriage-arresting teeth arranged at angles to each other and one of which at least is offset from the plane of the other teeth.

31. In a type-writing and tabulating machine, the combination with a carriage, of a denomination-determining mechanism, and a plurality of rows of column-stops, each row being arranged to be used for a different piece of tabular work.

32. A type-writing and tabulating machine, the combination of a carriage, a denomination-determining mechanism, and an adjustable bar constructed to carry a plurality of rows of column-stops, any desired row of which may be brought into coöperative relation with said denomination-determining mechanism by means of an adjustment of said bar.

33. In a type-writing and tabulating machine, the combination of a carriage, a denomination-determining mechanism, and a plurality of rows of column-stops movable as a whole to different working positions.

34. In a type-writing and tabulating machine, the combination of a carriage, a reversible carrier provided with rows of column-stops on different sides thereof, and means adapted to coöperate with the stops of each row to arrest the carriage.

35. In a type-writing and tabulating machine, the combination with a carriage, of a denomination-determining mechanism, a rod mounted for rotative adjustment, and a plurality of longitudinal rows of column-stops arranged on said rod and movable simultaneously thereby, so that by a rotation of said rod one row may be moved out of operative relation and another row may be moved into

operative relation to said denomination-determining mechanism.

36. In a type-writing and tabulating machine, the combination with a carriage, of a bar, column-stops arranged in different radial positions on said bar, denomination-stops movable into and out of position for coaction with the stops arranged at one side of said bar, and means for varying the position of said bar so as to bring different radial column-stops thereon into position for coaction with said denomination-stops.

37. In a type-writing and tabulating machine, the combination of a carriage, a bar thereon, column-stops arranged upon said bar and projecting in different directions, a series of denomination-stops mounted upon the framework of the machine, and means for adjusting the bar upon said carriage so as to bring different stops thereon into position for coaction with said denomination-stops.

38. In a type-writing and tabulating machine, the combination with a carriage, of a bar mounted to rotate thereon, a plurality of sets of radially-projecting column-stops arranged upon different sides of said rod, a series of denomination-stops supported upon the framework of the machine, and means for causing said denomination-stops to coöperate with said column-stops.

39. A bifurcated column-stop having a plurality of radiating stop-teeth.

40. A column-stop having oppositely-projecting stop-teeth.

41. A bifurcated column-stop having oppositely-projecting stop-teeth.

42. A stop notched at one side thereof and having projecting stop-teeth at the other three sides thereof.

43. A bifurcated column-stop having a plurality of stop-teeth which are out of line one with another.

44. A bifurcated column-stop having an offset stop-tooth.

Signed in the borough of Manhattan, city of New York, in the county of New York and State of New York, this 8th day of January, A. D. 1900.

GEORGE B. WEBB.
